UNITED STATES PATENT OFFICE.

JOSEPH N. WIGGIN, OF ORANGE, AND ROBERT W. CORNELISON, OF BLOOMFIELD, NEW JERSEY, ASSIGNORS TO H. B. WIGGIN'S SONS COMPANY, A CORPORATION OF NEW JERSEY.

DESIGN FOR WALL-COVERING.

No. 39,220.

Specification for Design.

Patented March 24, 1908.

Application filed March 14, 1907. Serial No. 362,425. Term of patent 14 years.

To all whom it may concern:

Be it known that we, JOSEPH N. WIGGIN, residing at Orange, in the county of Essex and State of New Jersey, and ROBERT W. CORNELISON, residing at Bloomfield, in the county of Essex and State of New Jersey, and each of us being a citizen of the United States, have invented a new, original, and ornamental Design for Wall-Coverings, of which the following is a specification, reference being had to the accompanying drawing, forming part thereof.

The figure is a plan view of a piece of wall covering showing our new design.

We claim

The ornamental design for wall covering, as shown.

JOSEPH N. WIGGIN.
ROBERT W. CORNELISON.
